UNITED STATES PATENT OFFICE

HERCULES DORN STEWART, OF LANCASTER, PENNSYLVANIA, ASSIGNOR TO ARM-
STRONG CORK COMPANY, OF LANCASTER, PENNSYLVANIA, A CORPORATION OF
PENNSYLVANIA

RUNNING BOARD

Application filed August 31, 1931. Serial No. 560,274.

My invention relates to a running board for automobiles, particularly to the provision of a cushioning strip that may be applied to the running board. It is an object of my invention to produce a cushioning member for running boards that will be inexpensive to manufacture. It is a further object of my invention to provide a cushioning member that may be applied to running boards with a minimum amount of trouble and which will remain in place for the life of the cushioning member. It is a further object of my invention to produce a running board that will enhance the esthetic beauty of the automobile to which it is applied. It is a further object of my invention to provide a cushioning member that may be made in any desirable color or combination of colors. It is a further object of my invention to provide a cushioning member that will be durable and which will retain its beauty throughout its life. Other objects of my invention will become apparent upon reading the annexed specification.

Cushioning strips of rubber attached to metal running boards by vulcanization or by suitable cements are well known. Such cushioning strips, however, are generally not particularly desirable because of the impossibility of attaining any pleasing decorative effects without skyrocketing the cost of the completed running board beyond reason. Running boards having cushioning strips formed entirely of rubber cannot be harmonized with the appearance of the rest of the automobile on a commercial scale.

The possibilities of obtaining decorative effects with linoleum are unlimited. However, linoleum is not satisfactory when used as a cushioning strip by itself because of the necessity of clamping the edges down on the running board with metal clamps. The presence of metal clamps on the exposed face of the linoleum detracts considerably from the appearance of the running board. Another objection to the universal use of linoleum as a cushioning strip for running boards is that many running boards are formed with compound curves. The linoleum

cannot conform to the contour of the compound curve.

With my construction I am enabled to utilize the flexibility of the rubber and the beautifying characteristics of the linoleum. 55 The linoleum may be of any desirable color or any combination of colors to form a suitable contrast with the rubber and to harmonize with the beauty of the automobile itself. 60

In the drawing forming a part of this specification I have illustrated a cross section through my running board to show the details of construction. In the drawing the reference numeral 1 indicates a suitably shaped metal running board. The running board has the strips 2 and 3 of rubber vulcanized thereto by any conventional means. The vulcanization of the rubber on the metal running board is of particular advantage in 70 cases where the running board has a compound curve. The vulcanized rubber and the metal running board constitute an integral structure and the rubber will conform intimately to the contour of the metal running 75 board.

The strip 3 has a depending flange 4 to cover the edge of the running board. This serves as a protecting means whenever anyone kicks the edge of the running board. It 80 also prevents the edge of the running board from becoming marred and unsightly from minor collisions. The strips 2 and 3 have on their inner edges over-hanging ledges 5 and 6 which serve as a retaining means for the cushioning strip 7. The strip 7 may be formed of any suitable cushioning material but is preferably formed of linoleum or similar composition. The linoleum composition may be formed on a backing of either felt or burlap. It is also possible to use a linoleum composition heavy enough and strong enough to be used on the running board without any backing material. The edges of the strip 7 are formed with suitable projections 8 and 9 to provide an interlocking engagement between the strip 7 and the ledges 5 and 6 on the rubber strips 2 and 3. Obviously the edges of the strips may be beveled, or any other suitable form of connection means may 95 100

be substituted for the overhanging ledges 5 and 6 and the projections 8 and 9.

The linoleum strip 7 may be held in place by means of the ledges 5 and 6 and metal clamps at each end of the strip. I prefer, however, to insure the adherence of the strip 7 to the running board by the use of a suitable adhesive. The adhesive is applied on the underside of the linoleum and the strip is then slid in place with its edges 8 and 9 in interlocking engagement with the overhanging ledges 5 and 6 of the two strips of rubber vulcanized in place on the metal running board. The cushioning strip 7 of linoleum or similar composition is securely locked in place by the overhanging ledges of the rubber strips and the adhesive. The strip will be held in place until it is completely worn out. Generally the strip will last longer than the car.

The strip 7 is provided on its top surface with a plurality of ribs 10 which take the brunt of the wear to which the running board is subjected. The ribs serve to protect the main portion of the cushioning strip 7 from wear and prolong its useful life. The ribs 10 are shown as longitudinal parallel projections. However, they may extend transversely of the running board or may be arranged in any suitable design. It is also within the purview of my invention to form the main portion of the cushioning strip 7 of one color and the ribs of a different color or colors to produce any desired artistic effect in the final product.

While I have described a preferred embodiment of my invention it will be understood that various details may be varied without departing from the spirit of my invention and I do not desire to limit my invention except by the appended claims.

I claim:

1. A running board comprising a metal base, two rubber strips vulcanized thereto and a strip of linoleum composition interlockingly engaged between the two rubber strips.

2. A running board comprising a metal base and a pair of spaced strips of rubber and a strip of linoleum secured thereto in interlocked engagement.

3. A running board comprising a metal base, two strips of rubber attached thereto, each strip having an overhanging ledge projecting from its inner edge, and a strip of linoleum composition adhesively secured to the base and having projections along its edges cooperating with the ledges of the rubber strips to maintain the linoleum in position.

4. A running board comprising a base, a strip of linoleum positioned on said base between a pair of strips of more resilient material, said linoleum strips being provided with projections adapted to cooperate with

said second mentioned strips to maintain said linoleum strips in position.

5. A running board comprising a base having a flat tread portion and a curved portion, a strip of linoleum secured to said flat portion and a strip of more resilient material secured to said curved surface, said strips being interlockingly engaged.

In testimony whereof I have hereunto set my hand.

HERCULES DORN STEWART.
